HIGH PRESSURE GAS DISPENSING SYSTEM

James J. Shanley, Bartlesville, Okla., assignor to
 Phillips Petroleum Company, a corporation of
 Delaware

Application February 19, 1940, Serial No. 319,786

24 Claims. (Cl. 62—1)

The present invention relates to improvements in devices for automatically changing withdrawal connections from one source of high pressure gas to another upon decrease in pressure in the first source.

Liquefied petroleum gas, such as propane, butane, or a mixture of the two, is now being marketed extensively in tanks or cylinders. In making use of this liquefied gas for operating gas consuming appliances, such as domestic gas ranges, it is customary to provide the customer with two containers with some means of connecting them to a service line through a suitable arrangement of valves and pressure regulators. The usual procedure is to use one of the cylinders as the active source of the gas supply, keeping the other cylinder as a reserve source until the first cylinder is exhausted. It is then necessary to cut off the exhausted source and establish connection with the reserve source. In prior practice, the valve on the active cylinder was opened while the valve on the reserve cylinder was kept closed. When the gas in the active cylinder became exhausted the valve on that cylinder was closed and the valve on the reserve cylinder opened. The disadvantage of this system was that the customer had to go to the place where the cylinders were housed, usually outside, and change the valves each time one of the containers became depleted. Sometimes, a container became depleted at night or while the customer was not at home and the result was that there was a cessation in the gas supply and all pilot lights were extinguished. Recently there have been developed various systems equipped with so-called automatic valves, whereby upon the pressure in the active container becoming low, the vapor in the reserve container will be drawn upon but the valve must be reset for a second cycle. For some time it has been desirable to produce a fully automatic changeover device that does not have to be previously set manually before it effects a changeover of withdrawal connections.

An important object of this invention is to provide an improved automatic changeover device that will be entirely automatic in its operation.

An additional object of the present invention is to provide an automatic changeover device of simplified construction and positive operation.

Other objects and advantages of this invention will become apparent from the following detailed description thereof, reference being had

to the accompanying drawings which constitute a part of this specification, and wherein:

Figure 1 is a view in vertical section of the changeover device.

Figure 2 is a view in cross section taken on the line 2—2 of Figure 1,

Figure 3 is an enlarged view in cross section of the spring retainer and unlatching mechanism.

Figure 4 is a view in elevation of the sleeve and unlatching mechanism.

Figure 5 is a view in vertical section of a modification.

Figure 6 is a diagrammatic view of the same modification.

Figure 7 is a view in vertical section of a further modification, and

Figure 8 is a diagrammatic view of a dispensing system.

Reference numeral 10 designates generally a casing which may be made up of many parts but is shown in only two parts 11 and 12 for purposes of simplicity in illustration. Between parts 11 and 12 a flexible diaphragm 13 is sealingly clamped. Diaphragm 13, including stiffening member 14 is rigidly secured to a tubular sleeve 15 by any desirable fastening means 16. Casing 10 is internally shaped at 17 and 18 to receive snugly, but slidably, hollow sleeve 15 at its extremities. The sliding connection between hollow sleeve 15 and the casing at 17 and 18 should be as sealing as possible consistent with free motion of sleeve 15. As will be described later, any slight gas leakage at this point is not consequential. Casing 10 further presents valve chambers 19 and 20 slidably receiving piston valves 21 and 22 which are spaced from the walls of the valve chambers 19 and 20 by fins 23 which allow gas to blow past the valves. It will be apparent that the outlet sides of valves 21 and 22 are exposed to a common pressure. Each valve having valve face 24 coating with a valve seat 25 on the casing is maintained in closed position by a relatively light spring 26. Springs 26 at the opposite end from their contact with valves 21 and 22 contact spring retainers 27 which are identical. Spring retainers 27 have reduced portions 28 slidably received by the same portions 17 and 18 of the casing which receive sleeve 15. Spring retainers 27 also each have a channel 29 which slidably receives integral extensions 30 on sleeve 15. Spring retainers 27 in the reduced portions 28 further have a peripheral channel 31 having flattened guide portions 31' (see Figure 2) which receives a closed ring 32 having an out-

side diameter substantially the same as that of reduced portion 28, of the same width as the channel 31 and half as thick as the channel is deep. A small leaf spring 33 tends to move the ring to the position shown in Figure 3 and flattened portions 32' on ring 32 coating with guide portions 31' of the channel limit the ring to vertical movement. Integral extensions 30 on sleeve 15 have cut out portions 34 which include cam surfaces 35 which on extreme movement of sleeve 15 engage ring 32 to bring it within the confines of reduced portion 28 of the spring retainer. Gas passages 36 and 37 connect the upstream side of valves 25 with the diaphragm chambers in the casing on separate sides of diaphragm 13. Passages 36 and 37 terminate in check valves 38 and 39 which act to prevent gas in the diaphragm chambers from returning into the gas passages. Bleeder ports 40 and 41 connect the diaphragm chambers with the interior of the hollow sleeve 15. A passage 42 connects the interior of the casing with the utility or service line which may include the usual second stage regulator, or if no first stage regulators are used at the cylinder, the system regulator.

In the operation of the device the spring retainers 27 are moved by gas pressure differential acting on diaphragm 13 at the time a cylinder becomes exhausted to bias the piston valve 21 and 22 nearest that cylinder by compressing one of springs 26, along the lines shown in Patent 2,138,989 of R. W. Thomas and Charles Mac-Sporran. Ring 32 then acts as a latch to hold that spring retainer in its biasing position until there is again a pressure differential operating on diaphragm 13 in the reverse direction at which time the opposite piston valve is biased. The cylinder nearest the piston valve thus biased will thus constitute the reserve cylinder.

Specifically, with no cylinders connected to the device and with the parts in the position shown in Figure 1, connection of a cylinder by means of a pigtail to the left hand side of casing 10 and with the gas pressure in the pigtail at ten pounds after reduction to that value by the first stage regulator, a pressure differential of ten pounds would act on diaphragm 13 through the medium of gas admitted to the left hand diaphragm chamber by passage 36 and check valve 38. The gas pressure in the right hand diaphragm chamber would be atmospheric due to bleeder port 41. Valve 22 would open to allow gas to flow past it and out passage 42 to the service line but the pressure differential acting on diaphragm 13 would move sleeve 15 to the right, carrying with it spring retainer 27. Valve 21 would thereupon have a greater spring force exerted upon it than valve 22 and when a cylinder is later connected to the pigtail associated with the right hand side of the device, the ten pounds acting on valve 21 would fail to open the valve for the reasons set out in the above mentioned patent. This same ten pounds, however, acting through passage 37 and check valve 39 would balance the pressure acting on the left hand side of diaphragm 13 and restore the sleeve 15 to its original or intermediate position. Right hand spring retainer 27, however, is prevented from returning to its original position by ring 32 which leaf spring 33 has forced up into eccentric position where the edge of ring 32 will engage the abutment in casing 11 formed by the junction of portion 17 and valve chamber 19. The right hand cylinder will thus be maintained in reserve and will only be drawn upon as explained later

when the left hand cylinder is exhausted or "freezes."

We will assume that valve 22 now causes a pressure drop of one pound whereas biased valve 21 would cause a pressure drop of three pounds to gas flowing past it. When the left hand cylinder becomes exhausted and the pressure therein and in the associated pigtail drops below ten pounds, the pressure in passage 36 will begin to drop below ten pounds and check valve 38 will close. The pressure at 42 which was nine pounds due to the one pound pressure drop over valve 22 will drop until it reaches seven pounds at which time valve 21 will open and the gas pressure at 42 will remain at seven pounds. Since the pressure in the pigtail associated with the left hand cylinder has continued to drop, valve 22 will close. The pressure in the righthand diaphragm chamber will be ten pounds corresponding to the pressure on the upstream side of valve 25. On the other hand the pressure in the left hand diaphragm chamber which was ten pounds will be dropping due to leakage of gas through bleeder port 40. This leakage will continue until the pressure in the left hand diaphragm chamber reaches seven pounds, the pressure in the interior of sleeve 15. However, diaphragm 13 is so designed that the resulting three pound pressure differential will move sleeve 15 and the lefthand spring retainer 27 to the left an extreme distance, limited if desired by contact of the spring retainer 27 with valve 22. Such extreme movement carries integral extension 30 on the righthand side of sleeve 15 into contact with the associated ring 32 and the cam surface 35 moves the ring so as to unlatch that spring retainer and allow it to move to the left, removing the bias from the associated valve spring 26. Bleeder ports 40 and 41 can be designed so that together with any leakage between sleeve 15 and the casing there will be a time factor present in the building up of the pressure differential in order that in case of freezing of the supply cylinder, it will have time enough to warm up and continue to act as supply cylinder with only a slight drain on the reserve.

When the empty cylinder is removed from the left hand side of the device and a new cylinder connected, diaphragm 13 will once more resume the position shown in Figure 1 but leaving left hand spring retainer 27 locked in spring biasing position so that the new cylinder will be in reserve.

It will be understood that the type of valves, latches, and other elements shown are purely to complete an operative combination and any suitable form of these elements may be substituted such as for example some form of valve having a lower pressure drop across it than a piston valve or a simpler form of latch. Further, it will be seen that leakage past sleeve 15 from the diaphragm chambers to the interior of the casing will not be of consequence since the pressure acting to cause this leakage is only a few pounds and most important the gas thus leaking passes into the utilization conduit or if the leakage is in the reverse direction, is stopped by check valves 38. If a perfect seal can be set up between sleeve 15 and the casing at 17 and 18 and still have sufficient movement as is done in the liquefied gas manual valves in the prior art, then check valves 38 and 39 and bleeder ports 40 and 41 might, if desired, be omitted and the change-over action would then take place only when the empty cylinder is disconnected. This would

necessitate, of course, that no check valves be interposed in the pigtails or the first stage regulators. Extensions 30 are of such a length that extreme movement of sleeve 15 will not disengage the operative latch before the other latch is in its eccentric position. Thus the cam surface 35 is spaced out far enough on the extension so that the spring retainer of the spring being compressed by spring 15 is moved past its initial latching position before the operative latch is moved from its eccentric position to a position within the boundaries of its spring retainer.

Figures 5 and 6 show an application of the general principles present in the device shown in Figure 1 to a system in which the changeover device is combined with one of the first stage regulators. In this embodiment a casing 100 is divided into three compartments by a pair of diaphragms 101, 102. The compartment farthest to the right and designated 103 is open to the atmosphere at port 104. This is the usual atmospheric pressure side of a regulator and has the usual spring 105, and spring adjustment device 106. The diaphragm 102 through pin 107 and linkage system 108 actuates tire valve core or any other suitable valve 109. The lower end of linkage 108 may connect with the usual "push pin," eliminating valve 109 and using the cylinder valve as the regulator valve.

On the end of pin 107 removed from diaphragm 102 a spring contact member 110 is screw threadedly mounted. Member 110 is contacted by spring 111 held by spring retainer 112, the threaded mounting of member 110 serving to adjust the counteraction function of spring 111. Spring retainer 112 has a reduced portion 113 slidably received by concentric support 114. Diaphragm 101 has an element 115 connected thereto for contacting spring retainer 112 to urge the same toward diaphragm 102. A ring 116 in the reduced portion 113 and an extension 117 on element 115 act in the same manner as the latch of 32 and extension 30 of Figures 1-4 inclusive.

A conduit 118 joins the usual first stage regulator 125 of an adjacent cylinder to the second stage regulator 126 of the system. This conduit 118 has a port 119 connected to the left hand compartment 120 and a passage 121 connected to the middle compartment 122. A check valve 123 is interposed in the conduit 118 between port 119 and passage 121. A check valve 124 is interposed in passage 121.

In the operation of this modification it is assumed that the first stage regulator 125 on the adjacent cylinder is set for an output pressure of 15 pounds. The tension of spring 105 is set so that with no counteracting force exerted on member 110 by spring 111, a pressure of 20 pounds in compartment 122 will close valve 109 and any smaller pressure there will result in the valve's being maintained open. In other words, diaphragm 102 and valve 109 will operate as a regulator with an output pressure of 20 pounds. By means of member 110 the pressure exerted by spring 111 on spring retainer 112 in its extreme latched right-hand position will be such that the action of spring 105 will be counterbalanced to the amount that a pressure of 10 pounds in compartment 122 will close valve 109. In this latter case, diaphragm 102 and associated parts including valve 109 will act as a regulator with an output pressure of 10 pounds.

Assuming that no cylinder is connected to the system, the connection of a full cylinder by means of the connector 127 on casing 100, with spring

5 retainer 112 in the position shown, a pressure of 20 pounds will be present in compartment 122 and gas at the pressure of 20 pounds will be fed to the second stage pressure regulator 126, check valve 123 acting to prevent this pressure from going toward the other cylinder. When a full cylinder is connected to first stage regulator 125, a pressure of 15 pounds will be present in conduit 118 to the left of valve 123 which will remain closed and a pressure of 15 pounds will be present in compartment 120. Diaphragm 101 will be slightly to the left of its intermediate position shown which will result in no pressure being applied to spring 111 by spring retainer 112.

When the cylinder connected to casing 100 is depleted and the pressure in compartment 122 drops below 15 pounds, check valve 124 will close and check valve 123 will open and gas at 15 pounds pressure will be fed to the second stage regulator from the cylinder connected to regulator 125. Diaphragm 101 will substantially remain at intermediate positions due to 15 pounds being present in compartment 120 and substantially 15 pounds in compartment 122. Diaphragm 102 will be maintaining valve 109 in wide open position. Removal of the cylinder connected to casing 100 will allow the small amount of gas in compartment 122 to go off through the open connection and the 15 pounds pressure in compartment 120 will then by means of diaphragm 101 move spring retainer 112 to the right into its latched position where it will force spring 111 into engagement with member 110 to act on diaphragm 102. When a full cylinder is now connected to casing 100, diaphragm 102 and valve 109 will allow pressure of only 10 pounds to build up in compartment 122. This will move diaphragm 101 to approximately its intermediate position but spring retainer 112 will remain latched in its extreme right hand position so that diaphragm 102 and valve 109 will now be acting as a regulator with an output pressure of 10 pounds. Check valve 124 will of course stay closed since there is still 15 pounds pressure present in conduit 118.

45 When the cylinder connected to regulator 125 is depleted and the pressure in conduit 118 drops below 10 pounds, check valve 123 will close and check valve 124 will open and gas will pass from compartment 122 to the second stage regulator. 50 With 10 pounds pressure in compartment 120 diaphragm 101 will remain at approximately its intermediate position until the cylinder connected to regulator 125 is disconnected and the small amount of gas in compartment 122 and conduit 55 118 to the left of check valve 123 will pass out through the regulator. Obviously no check valve should be used in regulator 125. The pressure in compartment 120 will then drop to atmospheric and the diaphragm 101 will move to its extreme 60 left hand position in which position extension 117 operates to unlatch ring 116 and diaphragm 102 and valve 109 will again be set to operate at 20 pounds, thus completing the cycle. It will be 65 observed that diaphragm 101 has minimum movement due to 5 pounds differential but its operating movement is due to 10 or 15 pounds differential. "Freezing" would be taken care of in this type changeover.

70 The usual indicator could be used in which the interstage pressure operates the signal. Pressures of 10 and 20 pounds would indicate that the cylinder connected to casing 100 is supplying the gas and 15 pounds, the other cylinder.

75 The casing 100 which has been shown quite

elongated to simplify the showing of the preferred forms of the elements, could be made not much larger nor more expensive than the usual regulator shown at 125. Any form of the elements shown would of course be usable so long as the principles are followed.

It can be seen that the device shown in Figures 1-4 inclusive could be used in the present high pressure or even low pressure pigtail systems by substituting diaphragm regulators for the piston valves 21 and 22, the diaphragms of which would be counterbalanced by springs 26 in the same manner as diaphragm 102 of Figure 5.

Such an arrangement is shown in Figure 7 wherein a casing is shown at 200 divided into six compartments 201, 202, 203, 204, 205, 206, by three flexible diaphragms 207, 208, 209, and two rigid partitions 210, 211. As will be apparent from further description, compartments 202 and 205 are in effect one compartment and might be so constructed. The same is true of compartments 201 and 206 which are open to the atmosphere and serve to protect the regulator diaphragms 207 and 209 in addition to positioning the usual regulator spring adjusting mechanism 212. A gas inlet 213 connectable to one source of gas opens into compartment 203 and a second gas inlet 214 connectable with a second source of gas opens in compartment 204, each inlet being closed against reverse flow by check valves 215. Regulator valves operable by diaphragms 207 and 209 are shown at 216 and 217 respectively and are operatively associated with their respective diaphragms by stem members 218 slidably carried by guides 219. As in Figures 1-4 inclusive a sleeve 220 fits in sealing relation with the casing at 221 and 222 and is associated in the same manner with spring retainers 223 having reduced portions 224, channels 225 and 226, rings 227, and unlatching extensions 228. As in Figure 5 the spring retainers 223 contact springs 233 which counteract the effect of the regulator springs 234. A gas outlet connectable to a gas utilization line is shown at 235.

The operation of this modification will be obvious from consideration of its similarity to the preceding modifications. With the parts in the positions shown and the regulators including diaphragms 207 and 209 set to give equal pressure on the outlet side of valves 216 and 217, connection of a source of gas under pressure to inlet 213 will cause diaphragm 208 to move to the right thereby increasing the degree of compression in right hand spring 233. This in turn changes the setting of the regulator including diaphragm 209 and reduces the output pressure at which valve 217 will operate. Due to the latching rings 227 the new setting will be maintained when a source of gas is connected to inlet 214 altho diaphragm 208 will move back to an intermediate position. Since the left hand regulator is still set for the original pressure, gas will be fed at this pressure to outlet 235. When the pressure of the source connected to inlet 213 declines to that of the output setting of the right hand regulator, the latter will begin to supply gas through valve 217. Check valve 215 in compartment 203 will prevent gas from flowing back through open valve 216 of that compartment. At the time valve 217 starts to supply gas, or if desired before this point but after the pressure of the source connected to chamber 203 declines below the value set for the left hand regulator, the changeover will take place thru extreme movement of diaphragm 208.

The changeover devices of Figures 1-4 inclusive and 7 may be used in a liquefied gas dispensing system of the type shown in Figure 8 where two sources of supply of liquefied gas are shown as containers 300 and 301 having first stage regulators 302 and 303 detachably connected to the containers at 304, 305. A conduit 306 connects the output side of each first stage regulator to the change-over device 307 the output side of which is connected to the system or second stage regulator 308 in service or utilization line 309.

While I have herein described and illustrated three modifications of my invention which are to be taken as preferred examples, it is to be understood that various changes may be made in size, shape, and arrangement of parts without departing from the spirit of my invention as expressed in the following claims.

I claim:

1. A system for storing and utilizing liquefied gas comprising two containers for the gas, a service line for connection with gas consuming appliances, a gas withdrawal conduit connecting each container to the service line, a valve controlling each withdrawal conduit, the outlet sides of the valves being exposed to a common pressure, valve operating means associated with the valves to set the same so that one valve remains closed until a minimum operating pressure is reached on the outlet side of the valves when said one valve opens, and gas pressure operated means associated with the valve operating means to change the setting so that the other valve remains closed until a minimum operating pressure is reached when said other valve opens.

2. A system for storing and utilizing liquefied gas comprising two containers for the gas, a service line for connection with gas consuming appliances, a gas withdrawal conduit connecting each container to the service line, a valve controlling each withdrawal conduit, the outlet sides of the valves being exposed to a common pressure, valve operating means associated with the valves to set the same so that one valve remains closed until a minimum operating pressure is reached on the outlet side of the valves when said one valve opens, gas pressure operated means associated with the valve operating means to change the setting so that the other valve remains closed until a minimum operating pressure is reached when said other valve opens, and means for applying the differential of the pressures present in the withdrawal conduits on the inlet side of the valves to the gas pressure operated means to actuate the same.

3. A system for storing and utilizing liquefied gas comprising two containers for the gas, a service line for connection with gas consuming appliances, a gas withdrawal conduit connecting each container to the service line, a valve controlling each withdrawal conduit, the outlet sides of the valves being exposed to a common pressure, valve operating means associated with the valves to set the same so that one valve remains closed until a minimum operating pressure is reached on the outlet side of the valves when said one valve opens, gas pressure operated means associated with the valve operating means to change the setting so that the other valve remains closed until a minimum operating pressure is reached when said other valve opens, means for applying the differential of the pressures present in the withdrawal conduits on the inlet side of the valves to the gas pressure operated means to actuate the same.

ated means to actuate the same, and latching means associated with the valve operating means to maintain the same in one setting.

4. A system for storing and utilizing liquefied gas comprising two containers for the gas, a service line for connection with gas consuming appliances, a gas withdrawal conduit connecting each container to the service line, a valve controlling each withdrawal conduit, the outlet sides of the valves being exposed to a common pressure, valve operating means associated with the valves to set the same so that one valve remains closed until a minimum operating pressure is reached on the outlet side of the valves when said one valve opens, gas pressure operated means associated with the valve operating means to change the setting so that the other valve remains closed until a minimum operating pressure is reached when said other valve opens, means for applying the differential of the pressures present in the withdrawal conduits on the inlet side of the valves to the gas pressure operated means to actuate the same, latching means associated with the valve operating means to maintain the same in one setting, and unlatching means associated with the gas pressure operated means, operable on predetermined pressure differential to release the latching means.

5. A system for storing and utilizing liquefied gas comprising two containers for the gas, a service line for connection with the gas consuming appliances, a gas withdrawal conduit connecting each container to the service line, a valve controlling each withdrawal conduit, valve operating means including a spring associated with each valve, and gas pressure operated means acting on said springs to change the influence of a spring on its associated valve.

6. A system for storing and utilizing liquefied gas comprising two containers for the gas, a service line for connection with gas consuming appliances, a gas withdrawal conduit connecting each container to the service line, a valve controlling each withdrawal conduit, the outlet sides of the valves being exposed to a common pressure, valve operating means associated with the valves to set the same so that one valve remains closed until a minimum operating pressure is reached on the outlet side of the valves when said one valve opens, gas pressure operated means associated with the valve operating means to change the setting so that the other valve remains closed until a minimum operating pressure is reached when said other valve opens, and means for applying the differential of the pressure present on the outlet side of the valves and the pressure present on the inlet side of a valve to the gas pressure operated means to actuate the same.

7. A system for storing and utilizing liquefied gas comprising two containers for the gas, a service line for connection with gas consuming appliances, a gas withdrawal conduit connecting each container to the service line, a valve controlling each withdrawal conduit, valve operating means associated with the valves to set the same so that one valve remains closed until a minimum operating pressure is reached on the outlet side of the valves when said one valve opens, gas pressure operated means associated with the valve operating means to change the setting so that the other valve remains closed until a minimum operating pressure is reached when said other valve opens, means for applying the differential of the pressure present on the outlet side of the valves and the pressure

present on the inlet side of a valve to the gas pressure operated means to actuate the same, and latching means associated with the valve operating means to maintain the same in one setting.

5 8. A system for storing and utilizing liquefied gas comprising two containers for the gas, a service line for connection with gas consuming appliances, a gas withdrawal conduit connecting each container to the service line, a valve controlling each withdrawal conduit, valve operating means associated with the valves to set the same so that one valve remains closed until a minimum operating pressure is reached on the outlet side of the valves when said one valve opens, gas pressure operated means associated with the valve operating means to change the setting so that the other valve remains closed until a minimum operating pressure is reached when said other valve opens, means for applying the differential of the pressure present on the outlet side of the valves and the pressure present on the inlet side of a valve to the gas pressure operated means to actuate the same, latching means associated with the valve operating means to maintain the same in one setting, and unlatching means associated with the gas pressure operated means, operable on predetermined pressure differential to release the latching means.

9. A system for storing and utilizing liquefied gas comprising two containers for the gas, a service line for connection to gas consuming appliances, conduits connecting the interior of the containers with the service line, a valve having an upstream side and a downstream side interposed in each conduit, valve operating means associated with each valve to actuate the valve in response to pressure conditions on the downstream side of the valve, adjustment means associated with the valve operating means to set the same so that one valve will open at a lower pressure than another, and gas pressure operated means for controlling the adjustment means acting in response to pressure differential between conduits on the upstream side of the valves.

10. An automatic changeover device comprising a valve structure having two inlets and an outlet, valves for the inlets, the outlet sides of the valves being exposed to a common pressure, valve operating means associated with the valves to set the same so that one valve remains closed until a minimum operating pressure is reached on the outlet side of the valves when said one valve opens, and fluid pressure operated means associated with the valve operating means to change the setting so that the other valve remains closed until a minimum operating pressure is reached when said other valve opens.

11. An automatic changeover device comprising a valve structure having two inlets and an outlet, valves for the inlets, the outlet sides of the valves being exposed to a common pressure, valve operating means associated with the valves to set the same so that one valve remains closed until a minimum operating pressure is reached on the outlet side of the valves when said one valve opens, fluid pressure operating means associated with the valve operating means to change the setting so that the other valve remains closed until a minimum operating pressure is reached when said other valve opens, and means for applying the differential of the pressures present in the withdrawal conduits on the inlet side of the valves to the fluid pressure operated means to actuate the same.

75 12. An automatic changeover device comprising

ing a valve structure having two inlets and an outlet, valves for the inlets, valve operating means associated with the valves to set the same so that one valve remains closed until a minimum operating pressure is reached on the outlet side of the valves when said one valve opens, fluid pressure operated means associated with the valve operating means to change the setting so that the other valve remains closed until a minimum operating pressure is reached when said other valve opens, means for applying the differential of the pressures present in the withdrawal conduits on the inlet side of the valves to the fluid pressure operated means to actuate the same, and latching means associated with the valve operating means to maintain the same in one setting.

13. An automatic changeover device comprising a valve structure having two inlets and an outlet, valves for the inlets, valve operating means associated with the valves to set the same so that one valve remains closed until a minimum operating pressure is reached on the outlet side of the valves when said one valve opens, gas pressure operated means associated with the valve operating means to change the setting so that the other valve remains closed until a minimum operating pressure is reached when said other valve opens, means for applying the differential of the pressures present in the withdrawal conduits on the inlet side of the valves to the gas pressure operated means to actuate the same, latching means associated with the valve operating means to maintain the same in one setting, and unlatching means associated with the gas pressure operated means, operable on predetermined pressure differential to release the latching means.

14. An automatic changeover device comprising a valve structure having two inlets and an outlet, valves for the inlets, valve operating means including a spring associated with each valve, and fluid pressure operated means acting on said springs to change the influence of a spring on its associated valve.

15. An automatic changeover device comprising a valve structure having two inlets and an outlet, valves for the inlets, the outlet sides of the valves being exposed to a common pressure, valve operating means associated with the valves to set the same so that one valve remains closed until a minimum operating pressure is reached on the outlet side of the valves when said one valve opens, gas pressure operated means associated with the valve operating means to change the setting so that the other valve remains closed until a minimum operating pressure is reached when said other valve opens, and means for applying the differential of the pressure present on the outlet side of the valves and the pressure present on the inlet side of a valve to the gas pressure operated means to actuate the same.

16. An automatic changeover device comprising a valve structure having two inlets and an outlet, valves for the inlets, valve operating means associated with the valves to set the same so that one valve remains closed until a minimum operating pressure is reached on the outlet side of the valves when said one valve opens, gas pressure operated means associated with the valve operating means to change the setting so that the other valve remains closed until a minimum operating pressure is reached when said other valve opens, means for applying the differential of the pressure present on the outlet

side of the valves and the pressure present on the inlet side of a valve to the gas pressure operated means to actuate the same, and latching means associated with the valve operating means to maintain the same in one setting.

17. An automatic changeover device comprising a valve structure having two inlets and an outlet, valves for the inlets, valve operating means associated with the valves to set the same so that one valve remains closed until a minimum operating pressure is reached on the outlet side of the valves when said one valve opens, gas pressure operated means associated with the valve operating means to change the setting so that the other valve remains closed until a minimum operating pressure is reached when said other valve opens, means for applying the differential of the pressure present on the outlet side of the valves and the pressure present on the inlet side of a valve to the gas pressure operated means to actuate the same, latching means associated with the valve operating means to maintain the same in one setting, and unlatching means associated with the gas pressure operated means, operable on predetermined pressure differential to release the latching means.

18. A system for storing and utilizing liquefied gas comprising two containers for the gas, a service line for connection with gas consuming appliances, a gas withdrawal conduit connecting each container to the service line, a valve controlling each withdrawal conduit, one valve being a check type valve opening in direction of the pressure from its associated container, valve operating means associated with the other valve set to control its output pressure, and gas pressure operated means associated with the valve operating means to change the setting of the same and thus the output pressure of the other valve.

19. A system for storing and utilizing liquefied gas comprising two containers for the gas, a service line for connection with gas consuming appliances, a gas withdrawal conduit connecting each container to the service line, a valve controlling each withdrawal conduit, one valve being a check type valve opening in direction of the pressure from its associated container, valve operating means associated with the other valve set to control its output pressure, gas pressure operated means associated with the valve operating means to change the setting of the same and thus the output pressure of the other valve, and the operating pressure in the conduit controlled by the check type valve being greater than one output pressure of the other valve and smaller than the other output pressure of the other valve.

20. A system for storing and utilizing high pressure gas comprising two containers for the gas, a service line for connection with gas consuming appliances, a gas withdrawal conduit connecting each container to the service line, a gas pressure regulator associated with each conduit for controlling the pressure of the gas delivered to the service line, one gas pressure regulator having a constant output pressure, adjustment means associated with the other regulator to change the output pressure of the same from low to a high value and vice versa, the low value of output pressure of the other regulator being lower than said constant output pressure and the high value of output pressure of the other regulator being above said constant output pressure.

21. An automatic changeover device comprising a valve structure having two inlets and an outlet, valves for the inlets, one valve being a check type valve opening in direction of the pressure from its associated container, valve operating means associated with the other valve set to control its output pressure, and fluid pressure operated means associated with the valve operating means to change the setting of the same and thus the output pressure of the other valve.

22. An automatic changeover device comprising a valve structure having two inlets and an outlet, valves for the inlets, one valve being a check type valve opening in direction of the pressure from its associated container, valve operating means associated with the other valve set to control its output pressure, fluid pressure operated means associated with the valve operating means to change the setting of the same and thus the output pressure of the other valve, and the operating pressure in the conduit controlled by the check type valve being greater than one output pressure of the other valve and smaller than the other output pressure of the other valve.

23. An automatic changeover device comprising a pair of conduits, a valve controlling one

conduit, a valve operating member for actuating the valve, adjustment means associated with the valve operating member, latching means associated with the valve operating member to maintain the same in one position, and unlatching means associated with the adjustment means to release the latching means.

24. A system for storing and utilizing high pressure gas comprising two containers for the gas, a service line for connection with gas consuming appliances, a gas withdrawal conduit connecting each container to the service line, means in each withdrawal conduit settable to control the pressure of gas withdrawn from the associated container, each control means preventing flow of gas in a direction from the service line toward the associated container, and adjustment means associated with one of the control means for varying the pressure setting between two values, the other control means having a constant normal pressure setting, one such value being higher than the normal pressure setting of the other control means and the other such value being lower than the normal pressure setting of the other control means.

JAMES J. SHANLEY.
